UNITED STATES PATENT OFFICE.

JOHN V. OSTERHOUT, OF BRIDGEPORT, CONNECTICUT.

ELECTRODE FOR SPARK-PLUGS.

1,373,907.

Specification of Letters Patent. Patented Apr. 5, 1921.

Application filed December 8, 1919. Serial No. 343,152.

To all whom it may concern:

Be it known that I, JOHN V. OSTERHOUT, a citizen of the United States, and a resident of Bridgeport, in the county of Fairfield and State of Connecticut, have invented 5 certain new and useful Improvements in Electrodes for Spark-Plugs, of which the following is a specification.

Where an internal combustion engine is 10 relied upon to furnish power in circumstances which do not admit of temporary failure, it is necessary to insure unfailing efficiency in the ignition of the fuel. In particular, the internal combustion engines 15 of aeroplanes must function without lapse. The existence of ignition trouble in such motors is very frequently a vital matter. It is therefore essential that the igniters for spark plugs used in such engines be unfailing in their operation.

Spark plugs used in engines of the above character may be of several types. For example, the central electrode may be incased in a large insulating core which extends 25 over substantially the entire length of the electrode and leaves only the firing point exposed. The intense heat existing during normal operation in the engine cylinder ultimately causes the fracture of this porcelain. Such fractured bits of material, if 30 falling in the explosion cylinder will score its sides and interfere with its successful operation. Even though the core is not broken by the heat, deposits of carbon are readily 35 formed upon it and short circuit the current, thus defeating the ignition function.

Another type of electrode avoids the use 40 of long insulating cores, and substitutes therefor a short insulating core with a long exposed portion of the central electrode. In this latter case the rod, of which the central electrode is composed, is subject to deflection and distortion by the heat and other conditions in the internal combustion engine. There results a material variation in 45 the gap between the central or primary electrode and the secondary electrode. This renders indeterminate and uncertain the uniformity of igniting sparks.

50 My invention is directed to the provision of a central electrode in a spark plug which shall retain the advantages of the rigidity found in an electrode sheathed for the greater part of its length by an insulating core; and 55 the freedom from fouling, short-circuiting and breaking, as in the type last described.

It is a further object of my invention to provide a central electrode which will hold its position definite regardless of variations in temperature or other surrounding conditions.

Other objects of my invention will be evident from the following description and drawings, in which—

Figure 1 is a longitudinal view, partly 65 broken away, of a spark plug and its central electrode;

Fig. 2 is a view of the central electrode; and

Fig. 3 is an end view of the same. 70 The customary form of spark plug embodying my invention is shown to consist of a jacket 4 having a screw-threaded sleeve 5 integral therewith. The extremity of the sleeve which projects within the explosion 75 chamber of the engine carries the secondary electrode 6 arched in toward the center of the sleeve.

A nut 7 screws into the opposite end of the jacket 4 and locks into close engagement 80 with the latter, an insulating core 8. This core 8 may consist of porcelain or other insulating material. The inner end of the core 8 carries the shoulder 9 and the short tapering extremity 10. The shoulder 9 is 85 locked in tight engagement with the internal shoulder 11 of the jacket by means of the nut 7.

The central electrode of improved form 90 passes through the core 8 and consists of the rod 12 screw-threaded as at 13 to receive a connection 14 with the ignition circuit. Surrounding the lower portion of the rod and abutting against the end of the tapering projection 10 is a collar or disk 15. The 95 lower end 16 of the electrode is cylindrical for a short distance as illustrated at 17. From the upper portion of the cylindrical part 17 to the outer edge of the collar 15 are a plurality of longitudinal fins or ribs 18. 100 Each rib has a knife edge 19. The ribs and collar are preferably formed integrally with the rod 12, although it is obvious that they may be constructed thereon if desired.

With the rod 12 mounted in the core 8 105 and extending into the explosion chamber so that its lowermost point is adjacent to the electrode 6, a large space is created around the rod. The core is restricted to the upper portion of the chamber, however, and its 110 insulating properties not liable to impairment by carbonization.

The electric current passes through the rod 12, jumps the gap by means of a spark and causes the explosion in the chamber. The reduced portion of the core 10 and the 5 extended ribs 18 will not be affected by the high degree of heat and other conditions. The ribs 18 for rigid supports to retain the central electrode 16 in its predetermined position regardless of any tendency to warp. 10 While the electrode is held in a rigid position there is no exposed insulating surface to become carbonized. There is no tendency of the short insulating porcelain 10 to fracture or become deteriorated in use. 15 The particular embodiment of my invention shown is, of course, susceptible of considerable variation without departing from the spirit of my invention, and it is to be understood that many changes may be made 20 by those skilled in the art, within the scope of the invention as defined in the appended claims.

What I claim is:

1. In a spark plug including a jacket, a lock-nut and a core, an electrode mounted in said core, said electrode having an extended bearing against the surface of the core and being braced against distortion. 25

2. In a spark plug including a jacket, a lock-nut and a core, a relatively long narrow rod constituting an electrode mounted in said core, a collar on the electrode and abutting against the core, and longitudinal tapering ribs extending from the collar toward the end of the electrode. 30

3. In a spark plug including a jacket, a lock-nut and a core, an electrode mounted in said core, a collar on the electrode and abutting against the core, longitudinal ribs extending from the collar toward the end 40 of the electrode, and a second electrode mounted on the jacket.

4. As an article of manufacture, an electrode for spark plugs including a rod, a median collar integral therewith and a plurality of tapering ribs surrounding said rod. 45

5. As an article of manufacture, an electrode including a rod, a median lateral enlargement thereof and bracing means extending from said enlargement outwardly along the rod. 50

In testimony whereof, I hereunto affix my signature.

JOHN V. OSTERHOUT.
